NUMERAL WHEEL REGISTERING MECHANISM

Alva G. Russell, Stamford, Conn., assignor to Pitney-Bowes, Inc., Stamford, Conn., a corporation of Delaware

Application July 1, 1955, Serial No. 519,479

12 Claims. (Cl. 235—136)

This invention relates to numeral wheel registering mechanism wherein numeral wheels of the differentially geared type have tens transfer mechanism of the creep-crawl type combined therewith.

The registering mechanism herein disclosed is particularly adapted for use in a postage meter.

In certain registering mechanisms which are used to register the values of postage printed, the tens transfer from a numeral wheel of lower order to a numeral wheel of higher order is accomplished by means of the well known Geneva type of transfer. The Geneva transfer has performed best in registering mechanisms where all values are entered through the numeral wheel of lowest order, but when the larger denominations of postage required the entry of two or more digit values, the Geneva type of transfer proved to be inadequate. Differentially driven counter wheels, when combined with Geneva transfer mechanism, proved effective in meeting the conditions of providing for the simultaneous entry of values of any denomination, but with the transfer operation limited to one tenth or 36° of the full rotation of the numeral wheel, the load which developed during this short period of transfer operation presented difficult problems, especially in a five bank meter where as many as four transfers could occur simultaneously.

In the creep-crawl system of tens transfer, as provided herein in combination with differentially geared numeral wheels, the difficulties offered by the Geneva transfer are corrected. Here, transfer is continuous during register wheel operation, that is, any value entered in any numeral wheel will have one tenth of the value simultaneously entered in the wheel of higher order.

However, the creep-crawl system of transfer presented its own problem in that after an initial register operation, the numerals on the numeral wheels were never in reading alignment. To provide for reading alignment, the numeral wheels are accordingly adjusted at the time it is desired to read same.

It is the general object of this invention, therefore, to combine tens transfer mechanism of the creep-crawl type with differentially geared numeral wheels which will meet the transfer and numeral reading conditions required in registering mechanism.

It is another object of the invention to provide transfer drive gearing between any register numeral wheel and a wheel of next higher order which will progressively effect the transfer rotation of each wheel of higher order, and to further utilize the same transfer drive gearing to effect rectification or adjustment of the numeral wheels to place the numerals in a correct reading position.

It is another object to provide a creep-crawl type of transfer for the numeral wheels of registering mechanism, also for the rectification of the numerals thereof for reading, through the use of compound gearing, and to maintain said gearing in a continuously meshed and driving relation with the differential drive of the numeral wheel during transfer and rectification operations.

It is also an object to provide a continuously geared

transfer mechanism directly driven from a numeral wheel of lower order to an adjacent numeral wheel of higher order to provide a 1—10 reduction drive to the latter wheel, and to combine therewith means whereby a part of the transfer gearing may be rocked to produce a planetary differential driving action to effect rectification of the numeral of the wheel of higher order for the purpose of numeral reading.

In the drawings:

Fig. 1 is a fragmentary view of a registering mechanism with parts broken away and taken in the direction of the arrow 1 on Fig. 2;

Fig. 2 is a vertical sectional view taken on the line 2—2 of Fig. 1;

Fig. 3 is a vertical sectional view taken on the line 3—3 of Fig. 1;

Fig. 4 is an enlarged vertical sectional view through two adjacent numeral wheels and associated tens transfer mechanism with the section differing for each wheel; and

Fig. 5 is a sectional view taken along the line 5—5 of Fig. 4.

Referring to the drawings in detail the register includes a group of numeral wheels 10 rotatable on a shaft 11 which shaft is supported within suitable side walls of a frame, one wall of which is shown at 12. Five numeral wheels are shown in Fig. 1 which wheels are adapted to be individually actuated by suitable actuator mechanism such as the type disclosed in Patent No. 2,657,593 or by any other suitable means. A value to be registered in the mechanism disclosed may vary from 1¢ to \$999.99. In a postage meter or any printing register, whatever value is set for printing is also set in the actuator mechanism to effect accumulation in the register wheels of the amount printed during a printing cycle of operation.

Each numeral wheel is differentially driven and includes a shell 13 having numerals 14 on its periphery in the order of "0" through "9." One end of the shell is closed, as at 15, while the opposite end has an opening 16 which is closed by means of a disk 17. A portion 18 of the disk fits within the shell opening 16 and may be secured thereto in any suitable manner.

A pair of planetary pinions 20 and 21 are rotatably mounted on stub shafts 22 and 23 which shafts are supported in the closed end 15 of the shell and in the disk 17. The pinions are so mounted as to be in overlapped engagement and are constantly in mesh with each other as shown in Fig. 5. The planetary pinion 20 also meshes with a sun gear 24 which is provided at the inner end of a hub 25. A gear 26 provided at the opposite end of the hub 25 is the main drive gear for the differentially driven numeral wheel. The hub 25 has a running fit within a bearing 27 provided in the disk 17 and further has a bore 28 which forms a bearing on the shaft 11.

The other planetary pinion 21 meshes with a sun gear 29 which is provided at the inner end of a hub 31. A gear 32 provided at the opposite end of the hub 31 is the transfer driving gear for the differentially driven numeral wheel. The hub 31 has a running fit within a bearing 33 provided in the closed end 15 of the shell 13 and further has a bore 34 which forms a bearing on the shaft 11.

It will be apparent from the description of the differentially geared numeral wheel that the wheel can be rotated in direct response to rotation of either the main driving gear 26 or the transfer gear 32, also when both gears 26 and 32 are simultaneously driven.

As shown in Fig. 1, the numeral wheels are spaced along the shaft 11 and each numeral wheel of lower order is connected with an adjacent numeral wheel of higher order by transfer gearing generally indicated at 35. It is to be noted that the transfer drive gear 32 of the numeral wheel of lowest order is locked against

rotation by a pin 30 projecting from the wall 12 into a tooth space of the gear 32.

Transfer is accomplished in a wheel of higher order during the entire rotation of an adjacent numeral wheel of lower order. A drive gear 36, provided as a part of the disk 17, meshes with a gear 37 which is freely rotatable on a shaft 38 supported by the walls 12. Said shaft 38 also provides a pivotal support for an inverted U shaped bracket 39 which bracket serves as a support for part of the transfer gearing 35. When rocked about the shaft 38, the bracket moves the gearing supported thereby in a planetary fashion to effect adjustment of the numeral wheel of higher order for the purpose of numeral reading.

The transfer gearing further includes a gear 41 which is integral with the gear 37 and meshes with a gear 42 rotatable on a shaft 43 carried by the bracket 39. A pinion 44 forms an integral part of the gear 42 and meshes with a gear 45 freely rotatable on the shaft 38. The final gear 46 of the transfer gear train is an integral part of the gear 45 and meshes with the transfer drive gear 32 of the numeral wheel of next higher order.

The transfer gearing above described is compounded in a manner to provide in a wheel of next higher order, one tenth of the degree of rotation of the adjacent numeral wheel of lower order.

Each transfer unit is retained against lateral movement by means of a plate 47, which, as best shown in Fig. 3, is supported on tie-rods 50-50 carried by the end supporting walls 12 of the frame. The side surfaces of said plates 47 are engaged by the full faces or a portion of the faces of the transfer gears above mentioned and has the upper edge portion thereof shaped to provide a semi-circular guiding edge 48, which edge is engaged by a hub 49 between the gear 42 and pinion 44.

Any desirable actuating means may be provided to enter values into the numeral wheels through their main driving gears 26, such as by the mechanism disclosed in Patent No. 2,657,593. An actuator gear 51 might be considered the equivalent of the intermediate gear of the patent, for example. Whatever the means of actuation, the gear 26 of a numeral wheel 10 will be driven during a cycle of operation in accordance with a pre-set value and one tenth of the value will transfer into the numeral wheel of higher order, with each numeral wheel of higher order than the numeral wheel which is actuated receiving one tenth of the amount of movement that has entered its adjacent wheel of lower order. In view of the continuous transfer action, the numerals of the register wheels move in spiral formation and hence the numerals are never in an aligned or normal reading position.

The transfer gears in the transfer gear train constantly remain in driving relation with the gear 36 and the transfer drive gear 32 of an adjacent numeral wheel of higher order. Further, said driving relation is maintained when the bracket 39 is rocked about the shaft 38 to adjust the numeral wheel of higher order to a reading position. The bracket movement is controlled by the position of a detented cam 52, the detents of which, as best seen in Fig. 4, are provided around the periphery of the numeral wheel disk 17, associated with an adjacent wheel of lower order. The detent cavity portions 53 are provided in varying depth with the least depth starting at the "0" position and increasing progressively through the "9" position, as indicated in Fig. 2.

Cooperating with the detented cam, to effect rectification of the numeral wheel for reading, is a rectifying pawl 54 which is pivotally positioned on a rod 55, carried by the walls 12 of the frame, and is normally urged toward the periphery of the detented cam 52. A tooth 56 on the pawl 54 is shaped to fit snugly into any of the detent cavities 53 when the rectifying pawl 54 is free for movement, and when the tooth is engaged therein, the numeral wheel associated therewith is in

its proper reading position. The rectifying pawl 54 has an arm 57 extending upwardly and around the numeral wheel as in Fig. 2, the end thereof passing to the inside of one side wall of the bracket 39. Said arm 57 has a pin 58 secured therein and projecting sidewardly through a cam slot 59 in the bracket 39. At the lower end of the rectifying pawl 54, a tail piece 61 is urged in the direction of a stop member 62 by a spring 63, which spring is stretched between an anchor rod 64 and a projecting portion 65 of the rectifying pawl. The stop members 62 are fixed to a shaft 66 and are arranged in a staggered relation on the shaft to first effect the release of the rectifying pawl 54 which is associated with the numeral wheel of lowest order, then the progressive release of each pawl of higher order.

Upon release, the rectifying pawl 54 will rock, thus causing the pin 58 to move within the cam slot 59 to effect rocking of bracket 39 in a counter-clockwise direction. Said rocking will cause the hub 49 between pinion 44 and gear 42 to ride over the guiding edge 48 of the plate 47. The bracket 39 also rotates about shaft 38 and carries therewith the shaft 43 on which the gear 42 and pinion 44 are free to rotate. Inasmuch as rectification takes place when the registering device is not in operation and initially involves only the transfer portion of an operation in a wheel of higher order, and inasmuch as the wheel of adjacent lower order is held fixed while initial rectification takes place, the gear 36 carried by the wheel of lower order and the compound gears 37, 41 in driving relation with said gear 36 are therefore also in a fixed position.

As the bracket 39 moves, during rectification, the gear 42 is driven about the fixed gear 41. The movement of the bracket 39 under control of the detented cam, and the reduction ratio of gears 44-45, effects a resulting movement through gears 46, 32 and the differential gearing within the numeral wheel to provide sufficient rotation for the return of the numeral of the wheel of higher order to an approximate reading position. Final and exact rectification takes place during the initial rectification of the next wheel of higher order when the tooth 56 of the rectifying pawl 54, associated with the numeral wheel of lower order moves into the detent cavity 53 which had been previously adjusted during its rectifying operation.

It is thus apparent that final rectification is associated with the numeral wheel of lower order, also, that the rectifying pawls 54 are released in a progressive order starting with the wheel of lowest order. Release of the first rectifying pawl 54 associated with the units wheel upon removal of the stop member 62 from the tail piece 61, during rotation of the shaft 66, will effect the adjustment of the tens numeral wheel before the tooth 56 becomes seated in the detent cavity 53 associated with the units wheel. Further rotation of the shaft 66 will next cause the stop 62a to be removed from the tail piece 61a of the rectifying pawl 54a, thus initiating rectification of the hundreds wheel while the tooth 56a effects final adjustment of the tens numeral wheel and so on.

Through the above described arrangement, therefore, each wheel of higher order, beginning with the tens wheel, receives its initial adjustment by the action of the release of the rectifying pawls of the wheel of adjacent lower order. This arrangement of rectification always places the wheel of higher order in a position where the pawl tooth 56 is opposite a detent cavity and never opposite the high point of the detent. It is thus impossible for the points of the detent and pawl to engage end on end. When the pawl 56 finally engages a detent cavity, the numeral wheel is firmly locked. After all of the rectifying pawls are in the latter position, all of the numeral wheels are in absolute alignment for reading.

Return of the numeral wheels to their normal positions for further actuation is accomplished when cam portions 67, 67a-b-c-d of the stop members 62,

fer driving gear with differential gearing between said driving gears and the numeral wheel, an actuator gear meshed with the main driving gear, a gear rotatable with the numeral wheel, transfer mechanism comprising a reduction gear train having a continuously meshed driving connection between the gear which is rotatable with the numeral wheel and the transfer driving gear of a wheel of next higher order, a movable member supporting the transfer mechanism and pivotally positioned to provide for planetary movement of the teeth of one gear around the teeth of the gear which rotates with the numeral wheel when said numeral wheel and gear occupy a stationary position at the end of an operating cycle, said movement of the gear effecting a reverse drive of the gear train and the consequent drive of the transfer driving gear of the wheel of next higher order for the adjustment of said wheel to position it for reading, a rectifying cam rotatable with each numeral wheel and having peripheral detent cavities varying in shape and depth in accordance with the movement required of the movable member, and means to move the movable member about its pivot including a detent engaging element operable to engage a detent cavity of a cam associated with a numeral wheel of adjacent lower order, whereby after adjustment of the higher order numeral wheel the lower order wheel is precisely adjusted to and locked in a line reading position.

10. A register mechanism having a plurality of numeral wheels each wheel having a main driving gear and a transfer driving gear with differential gearing between said driving gears and the numeral wheel, an actuator gear meshed with the main driving gear, a gear rotatable with the numeral wheel, transfer mechanism comprising a reduction gear train having a continuously meshed driving connection between the gear which is rotatable with the numeral wheel and the transfer driving gear of a wheel of next higher order, a movable member supporting the transfer mechanism and pivotally positioned to provide for planetary movement of the teeth of one gear around the teeth of the gear which rotates with the numeral wheel

5 when said numeral wheel and gear occupy a stationary position at the end of an operating cycle, said movement of the gear effecting a reverse drive of the gear train and the consequent drive of the transfer driving gear of the wheel of next higher order for the temporary adjustment of said wheel to position it for reading, a rectifying cam rotatable with each numeral wheel and having peripheral detent cavities varying in shape and depth in accordance with the movement required of the movable member, a 10 rocker lever operably connected with the movable member and including a detent engaging element normally urged in the direction of a detent cavity, a stop normally retaining the detent engaging element in non-engaging position relative to a cavity, and means to release the rocker lever to first effect adjustment of the movable member and gear train and finally to effect engagement of the detent engaging element with the detent cavity of a cam associated with a numeral wheel of adjacent lower order, whereby the numeral wheels are adjusted to and 15 locked in a line reading position.

11. Registering mechanism comprising at least two numeral wheels, creep crawl reduction transfer gearing between said numeral wheels to provide continuous transfer from any wheel of lower order to a wheel of higher order, 20 and means to effect adjustment of the transfer gearing while the gears remain in their original meshed transfer driving relation, whereby the numeral wheel of higher order is returned to a reading position when desired.

12. Registering mechanism comprising at least two differentially geared numeral wheels, creep crawl reduction transfer gearing between said numeral wheels to provide continuous transfer from any wheel of lower order to a wheel of higher order, and means to effect adjustment of the transfer gearing while the gears remain in their 25 original meshed transfer driving relation, whereby the numeral wheel of higher order is returned to a reading position when desired.
